The ornamental design for a container for foodstuff, as shown and described.

DESCRIPTION

FIG. 1 is a bottom perspective view of a container for foodstuff in accordance with the present invention;

FIG. 2 is a bottom plan view thereof, shown at a reduced scale;

FIG. 3 is a right side elevation view thereof, the left side being a mirror image thereof; and,

FIG. 4 is a front side elevation view thereof, the back side being a mirror image thereof.

A top plan view has been omitted as it does not form a portion of the claimed design.

The evenly dashed broken lines in the drawings illustrate the portions of the design that form no part of the claim. The dot-dot-dash broken lines in the drawings define the bounds of the claim and form no part thereof.
